H. EGASHIRA.
PHOTOGRAPHIC TRANSFER PAPER.
FILED SEPT. 18, 1919.

Hamki Egashira Inventor
By Alexander G. Sowell, attorney

UNITED STATES PATENT OFFICE.

HARUKI EGASHIRA, OF TOKYO FU, JAPAN.

PHOTOGRAPHIC TRANSFER PAPER.

Application filed September 18, 1919. Serial No. 324,448.

To all whom it may concern:

Be it known that I, HARUKI EGASHIRA, a subject of Japan, residing at No. 318 Tsunohazu, Yodobashi Machi, Toyotama Gun, 5 Tokyo Fu, Japan, have invented certain new and useful Improvements in a Photographic Transfer Paper; and I hereby declare that the following is a full, clear, and exact description thereof, reference being 10 had to the accompanying drawings, which form part of this specification.

This invention relates to a photographic transfer paper consisting of smooth paper coated with a thin transparent film formed 15 by spreading upon the paper a solution of nitro-cellulose or any other cellulose ester, and spreading over the film thus formed a sensitive emulsion of a silver salt and gelatin. The object of this invention is to obtain a 20 photographic transfer paper which, when it is pasted upon any surface, leaves thereon the photographic image, covered with a transparent film of nitro-cellulose or the like, the paper being easily peeled off.

25 The present wide application of photography to industrial and artistic purposes demands a large supply of negative plates of large sizes, but they are very expensive.

In order to meet this growing demand 30 for large size plates cheaply, it has been proposed to use what is known as negative paper. According to this method, paper coated with a sensitive emulsion, is directly exposed in a camera; and after developing

35 and fixing the image, the paper is made transparent by soaking it with wax or the like. However although the paper becomes transparent to sight, its constitution not being changed and its fibres remaining the

40 same, the transmission of light is by no means uniform all over the paper, and consequently, it is impossible to print therefrom clear positive pictures. Another method is to form a film of gelatin on paper

45 and to coat the film with a sensitive emulsion. Then after exposing the paper and developing and fixing the image, the whole is pasted on glass or the like, and the paper is stripped off, thus leaving on the glass the

50 film of gelatin with the image fixed thereon. However according to this method, the gelatin film sticks to the paper, and even when treated in warm water, it is not an easy task to peel off the paper. Moreover gelatin films being very brittle, they are very diffi-

cult to handle, and this method is not of practical use.

The present invention is an improvement in the above processes, and the following is an example of carrying it into practice, reference being had to the accompanying drawing:—

The accompanying drawing shows a vertical section, much enlarged, of my transfer paper, part thereof represented therein being 65 separated from the support.

I spread evenly on a surface of smooth paper 3 a thick solution of collodion, to form a thin, transparent and smooth layer 2 of nitro-cellulose by volatilizing the ether and 70 the alcohol. In the dark room I then coat the nitrocellulose layer with a sensitive emulsion, the principal ingredients of which are silver bromid and gelatin, and dry it thus forming a sensitive layer 1. Thus my 75 invention is something like a common bromide paper but has a film of nitro-cellulose between the paper and its sensitive film.

To use the transfer paper of my invention as a positive, it is exposed and the image is 80 developed and fixed in the same manner as an ordinary dry plate. I then spread on glass or the like to which the photographic image is to be transferred a 3% solution of gelatin, and when dried, immerse it in water 85 and place on it carefully the developed and fixed transfer paper. I then take the whole out of the water, and squeeze it and dry it slowly. When nearly dry, I peel off the paper, which comes off very easily leaving 90 behind the photographic image covered with a transparent film of nitro-cellulose.

I am aware that before my invention there was known a photographic transfer paper 95 consisting of a waxed paper coated with a substratum of a powdery nitro-cellulose deposited from an aqueous ethereal alcoholic solution, on which a sensitive gelatin emulsion is spread, such as the one described in United States Patent No. 1,299,479, Apr. 8, 100 1919, granted to Frank William Kent and Thomas Percy Middleton. However according to this process, a friable, rotten or porous substratum of powdery nitro-cellulose is formed upon a waxed paper, in order 105 to avoid the repellent nature of the waxed paper, thereby uniform coating thereof with a sensitive gelatin emulsion being made possible. The object of using nitro-cellulose in this process is, therefore quite different from 110

that in my invention. Moreover, in this process, the photographic image is not covered by a transparent film. Therefore the above process is entirely different from my 5 invention.

My transfer paper transferred to glass can be used as a negative and is just as good as any dry plate. When the transfer paper of this invention is used as a negative, it is 10 pasted on a glass plate or the like, before exposure, and then it is stripped. The image can be enlarged or reduced, and thus printing plates for collotype, offset, and the like, of any desired size can be manufactured by a very simple method. My transfer papers may also be used for printing 15 positive images on them, and when such positive pictures are pasted on metallic plates, porcelain, wood, bamboo, opalescent 20 board or the like, artistic and tasteful photographs will be obtained. When such positive pictures are pasted on glass, they can be used for magic lanterns. Thus the application of the transfer paper of my invention 25 is very wide.

My photographic transfer paper is usable in two ways; to wit, either as positive or as negative. When the transfer paper of this invention is used as a positive, it is 30 pasted on other paper, glass, wood plate, or porcelain plate, after the image is developed, and then it is stripped and transferred; when used as a negative, the transfer paper is pasted on glass plate or the like, before 35 exposure, and then it is stripped.

Claims:

1. A photographic transfer paper comprising a smooth support paper, a layer of cellulose ester on the surface of the smooth 40 paper, and a sensitive emulsion layer on the cellulose ester layer, the emulsion layer and the cellulose layer together forming a film adapted to be separated as one from the support paper substantially as and for the purposes hereinbefore set forth.

2. A photographic transfer paper comprising a smooth support paper, a layer thereon formed by applying a solution of cellulose ester to the surface thereof, and a 50 sensitive emulsion layer on the cellulose ester layer; the two layers forming a film adapted to be separated from the support paper substantially as and for the purposes hereinbefore set forth.

3. A photographic transfer paper, comprising a smooth paper having a collodion layer and a layer of an emulsion of silver bromid and gelatin on said collodion layer; the two layers forming a film easily separable from the support paper, substantially as and for the purposes hereinbefore set forth. 55 60

4. A photographic transfer paper consisting of a smooth surfaced paper; a layer of cellulose ester on the smooth surface of said paper formed by applying a solution of such ester to the paper and drying it; and a sensitive emulsion layer upon the nitrocellulose ester layer, formed by spreading a sensitive emulsion over the ester layer, after the latter is dried; the emulsion layer and the cellulose ester layer being separable together as one film from the paper, substantially as and for the purpose described. 65 70

5. A photographic transfer paper, consisting of a smooth support paper, a dried collodion solution layer thereon, and a layer of sensitive emulsion, having for its chief ingredients silver bromid and gelatin on the collodion solution layer: the film formed by 80 the collodion and the sensitive emulsion layers being easily separable from the support paper, substantially as and for the purposes hereinbefore set forth. 75

6. The herein described method of making photographic transfer papers, consisting in applying a solution of cellulose ester to the surface of smooth paper to form a layer thereon, then coating such layer in a dark room with a sensitive emulsion, the sensitive 85 emulsion and the cellulose ester being separable as one film from the support paper after development, substantially as and for the purposes hereinbefore set forth. 90

7. The herein described method of making photographic transfer papers, consisting in first coating smooth paper with a collodion solution, and after drying spreading on the collodion layer a layer of a sensitive emulsion of silver bromid and gelatin, thereby 95 forming a film, consisting of the collodion and sensitive emulsion layers, easily separable from the support paper, substantially as and for the purposes hereinbefore set 100 forth. 105

In testimony that I claim the foregoing as my own, I affix my signature.

HARUKI EGASHIRA.
